ELECTRIC LAMP AND BULB

Michael E. McGowan, Bloomfield, N. J., assignor
to Westinghouse Electric Corporation, East
Pittsburgh, Pa., a corporation of Pennsylvania

Application September 3, 1943, Serial No. 501,075

8 Claims. (Cl. 176—32)

1

This application is a continuation-in-part of my copending application, Serial No. 345,310, filed July 13, 1940, for "Method of sealing-in and molding lamp bulbs," which is a division of what is now Patent No. 2,212,842, dated October 27, 1940.

This invention relates to bulbs, such as those for incandescent electric lamps and similar devices, and more particularly to such having their necks shaped to form an annular abutment to provide a seat for the edge of the lamp base.

The manufacture of devices for lamps of the above character, such as incandescent electric lamps, includes the operation of uniting what is termed a stem or mount, including a glass flare tube, to the neck portion of a bulb. In addition to the sealing-in operation, it is desirable to shape the united parts, while still plastic, so that when completing the lamp another part termed the base may more readily be applied and held in fixed relation to the bulb.

The present invention includes a bulb with its neck formed or shaped to receive a base. The formation of the bulb neck is important and has been accomplished heretofore by molding members, such as shown in Patent No. 2,006,231, dated June 25, 1935. This patent shows a bulb neck formed to receive a base but, as will be noted, the contour of the neck in cross section involves rounded surfaces. This follows the practice of avoiding sharp corners although it is of great advantage to provide a flat shoulder to hold the base, particularly when used with what is termed a mechanical base, when the latter is held by tabs or the like instead of cement.

The present invention provides the bulb neck with a sharp or substantially right angular shoulder or annulus to form a flat face or contact surface which cooperates with other means to hold the base against relative movement when attached to a bulb neck. Although a sharp cornered shoulder is contrary to previous teachings and practice, bulbs shaped in accordance with the present invention have been subjected to the usual tests, including the storage of lamps over a period of months for the determination of developed cracks, and it was found that they were free from undesirable internal stress and developed an extremely low percentage of cracks and leaks.

An object of the present invention is, therefore, to provide a lamp bulb having a neck portion formed with a shoulder of substantially right angular form in cross section and free from detrimental strains or cracks.

2

A further object of my invention is a lamp bulb with a neck portion specially formed for the reception of a base.

Other objects and advantages of the invention will become apparent as the description proceeds.

Referring to the drawings:

Fig. 1 is an elevational view of a lamp embodying my invention.

Fig. 2 is an enlarged fragmentary view of the neck portion of the lamp bulb shown in Fig. 1, before application of the base.

Fig. 3 is a bottom plan of the bulb shown in Fig. 2.

Fig. 4 is a view corresponding to Fig. 2, but showing a bulb neck and applied base partly in section.

Fig. 5 is a fragmentary view corresponding to Fig. 4 but showing a prior lamp bulb and base connection.

20 Although the present application relates only to a lamp and bulb portion thereof, yet such a bulb is desirably constructed with the use of a machine as described and claimed in Patent No. 2,212,842, dated August 27, 1940, the method desirably employed being described and claimed in my copending application, Serial No. 345,310, filed July 13, 1940, so it is not necessary in the present case to describe said machine and method.

25 Referring to the drawings in detail, there is shown a lamp 10 comprising a bulb portion 11 and a metal base portion 12. The bulb portion of the present embodiment comprises a main or generally spherical portion 13 and a neck or generally cylindrical portion 14 which connects with the 30 generally spherical portion by an approximately frusto-conical portion 15. The frusto-conical portion 15 is united with an intermediate cylindrical band 16 by an annular portion 17, forming an external shoulder 18 lying in a plane disposed 35 at right angles to the axis of the bulb or neck thereof. The outer surfaces of the portions 16 and 17 make a fairly sharp external right angle 40 19, as indicated most clearly in Figs. 2 and 4.

45 Enclosed in the neck portion of the bulb is the lamp mount 21 comprising a flare tube 22 having a press 23 through which lead-in conductors 24 and 25 extend to a filament 26. The filament may be supported from an arbor 27 extending from the press 23, as by means of wire 28, in a 50 conventional manner as will be understood. The flare tube 22 also includes an exhaust tube 29 communicating with the interior of the bulb by means of aperture 31 adjacent the press 23. The bottom, or external portion 32 of the flare tube, 55 is generally annular and perpendicular to the axis

of the bulb 11. It connects with the cylindrical band 16 by a generally cylindrical portion 33 of lesser diameter than the cylindrical band 16. The cylindrical portions 16 and 33 are connected by flaring or curved portion 34, as is most clearly shown in Figs. 2 and 4.

The external diameter of the cylindrical band 16 corresponds closely with the internal diameter of the edge portion of the associated threaded base 12 so that said base, when applied as shown in Fig. 4, is centered closely thereby with said edge portion, preferably corresponding in diameter with the maximum or crest diameter of the threads 36, in tight engagement with the shoulder 18 in the angle 19, except for the tight clamping of the lead-in conductor 25 therebetween. The other lead-in conductor 24 extends through and is soldered to the center contact 35 of the base.

The diameter of the smaller cylindrical portion 33 desirably corresponds approximately with the internal or root diameter of the threads 36 on the base, although it may be enough smaller to allow for a desired amount of cement 37 to be disposed therebetween, as shown in Fig. 4. If desired, indentations or grooves 38 may be provided in the cylindrical portion 33 to increase the bond between the bulb neck and the securing cement.

Heretofore in the molding of a bulb neck it has been the practice to carefully avoid any sharp corners, as illustrated for example in Fig. 5, where neck portion 14^a of the bulb 10^a which may have conventional indentations 38^a, is shown connected to the base 12^a by cement 37^a, but with no right angular shoulder and without any cylindrical portion embraced by the unthreaded edge of the base, as in Fig. 4. The reason for this prior construction is that it was believed that sharp bends or angular shoulders would subsequently cause cracks by reason of strains set up in the glass. In lamp making, however, it is of great advantage to provide a sharply defined shoulder, especially in cases where it is necessary or desirable to have a close fit between a base and a bulb neck, as illustrated in Fig. 4.

I have, therefore, ignored prior teachings in making the present invention and provided a bulb so formed that the neck is shaped with a right angular shoulder or abutment 18, and by reason of the method of sealing and shaping, as described in the copending application and parent patent referred to, the bulbs are found to be free from detrimental strains. Tests, including the manufacture and storage of bulbs so made, clearly shows that when produced in accordance with my invention they are free from cracks and resist the rough handling attending shipment as well as the lamps made heretofore, if not to a greater extent.

The bulb neck is formed so that it provides a cylindrical plug or extension 33 with a relatively sharp edge 39. Between said plug and adjacent to the abutment 18 is formed the ring 16 which is desirably so proportioned that it snugly fits the inner surface of the unthreaded portion of the associated base 12, which is usually in the form of a metal shell. Thus when a base is positioned to surround the bulb neck it is fitted to the surface of the ring 16 and pressed against the seat of abutment 18. The extension 33 desirably corresponds generally with the minimum diameter of the base threads and flares outwardly on a concave surface 34 to unite with the ring or cylindrical portion 16.

The hereinbefore mentioned advantages attributed to the special form of bulb neck have been used in connection with a base to be secured by mechanical means, such as shown and described in my Patent No. 2,119,681, dated June 7, 1938. The abutment and sharp corner formation is of great importance, however, in connection with cement-secured bases, as illustrated in Fig. 4. With the construction shown in this figure, the base, whether of plain tubular or threaded form, desirably frictionally fits the bulb neck at the cylindrical portion 16 and it has been found that when basing cement is employed, the quantity necessary is relatively small and that a fraction of the amount ordinarily used serves to hold the base in place. By making the abutment and annular seat and by proportioning the lower end 33 of the extension of such diameter as to contact the inner surface of the threaded portion of the base, when a threaded base is used, such a base is held against lateral movement and the only duty of the cement is to prevent relative endwise movement.

The structural arrangement of the bulb neck and base is such that very little strain is imposed on the cement and the base is effectively prevented from rocking. A very thin layer of cement serves to hold the base against removal, resulting in economy which is an important factor in connection with articles such as incandescent electric lamps produced in great quantities.

Although a preferred embodiment of my invention has been disclosed, it will be understood that modifications may be made within the spirit and scope of the appended claims:

I claim:

1. A bulb comprising a neck portion in the form of a plug with a plain cylindrical portion for axial insertion into a base, an annular abutment extending from said neck portion, said abutment having a surface disposed in a plane substantially normal to the longitudinal axis of said bulb to seat the upper edge of said base.

2. A bulb comprising a neck portion in the form of a plug for axial insertion into a base, an annular abutment extending from said neck portion, said abutment having a surface disposed in a plane substantially normal to the longitudinal axis of said bulb to seat the upper edge of a base, and a cylindrical surface adjacent to said abutment and proportioned to firmly contact with the interior surface of said base adjacent to said edge.

3. A bulb comprising a neck portion in the form of a plug for axial insertion into a standard threaded base having the inner diameter of the threaded portion less than the upper portion adjacent to the edge thereof, an annular abutment integral with said bulb and having a surface lying in a plane normal to the longitudinal axis of said bulb to provide a seat for the edge of said base, said plug having a cylindrical surface proportioned to fit said upper portion of said base and a portion of less diameter to allow it to fit within said threaded portion.

4. A bulb comprising a generally cylindrical neck portion extending below a shoulder integral with the bulb, and joined to said shoulder by a cylindrical ring portion having a diameter intermediate that of the shoulder and neck portion, and connected to the latter by a curved flaring portion, said shoulder having a surface disposed in a plane substantially normal to the longitudinal axis of the bulb.

5. A lamp comprising a main generally spheri-

cal bulb portion with an elongated or neck portion extending therefrom and enclosing a flare tube, said neck portion having a shoulder in a plane substantially perpendicular to the bulb axis, the part of said neck portion beyond said shoulder being cylindrical and terminating in an inwardly curved portion connecting with a generally cylindrical portion of lesser diameter than said cylindrical part, and said generally cylindrical portion being united to said flare tube by an annular portion of the latter.

6. In combination, a bulb comprising a generally cylindrical neck portion extending below a shoulder integral therewith, said shoulder having a surface disposed in a plane substantially perpendicular to the longitudinal axis of the bulb, and a base cemented to said neck portion and comprising a generally cylindrical edge portion fitting said generally cylindrical neck portion and abutting said shoulder.

7. In combination, a bulb comprising a neck portion terminating in a generally cylindrical portion joined to a shoulder thereon, lying in a plane substantially normal to the bulb axis, by a flaring portion and cylindrical band of a diameter intermediate said neck and generally cylindrical portion, and a metal base member threaded to fit a socket and having an edge portion corresponding in diameter with the crests of said threads and fitting said cylindrical band, the root diameter of said threads corresponding with the generally cylindrical portion, and means disposed between said threads and generally cylindrical portion for securing said base to said bulb.

8. A bulb comprising a neck portion in the form

of a plug, for insertion into a base formed as a hollow generally-cylindrical portion substantially closed at the bottom by an insulator portion carrying a center contact, threaded, and having a plain portion near its free edge, and a lateral extension integral with said bulb and forming a shoulder disposed in a plane substantially perpendicular to the longitudinal axis of the bulb to seat the upper edge of such a hollow base portion, said plug near the extension being proportioned to contact with the interior wall of the plain portion of said hollow base portion, to cooperate with said lateral extension and hold the base aligned with said bulb.
